UNITED STATES PATENT OFFICE.

JAMES J. COOK, OF JERSEY CITY, NEW JERSEY, ASSIGNOR TO COOK KEROSENE CARBURETOR COMPANY, A CORPORATION OF NEW JERSEY.

CARBURETER FOR EXPLOSIVE-ENGINES.

No. 838,085.

Specification of Letters Patent.

Patented Dec. 11, 1908.

Application filed January 8, 1904. Serial No. 188,217.

To all whom it may concern:

Be it known that I, JAMES J. COOK, a citizen of the United States, residing at Jersey City, in the county of Hudson and State of New Jersey, have invented a new and useful Carbureter for Explosive-Engines, of which the following is a specification.

This invention relates particularly to that class of carbureters employed in vaporizing oils for use as the motive agent of explosive-engines, though said invention may be useful for other purposes.

One of the objects of the invention is to provide an improved device of this character which may be easily attached to any oil, gas, or explosive engine and will thoroughly vaporize hydrocarbon oils, whether light or heavy, and with great economy.

A further object is to provide novel means of an automatic nature for securing the feed of a desired amount of oil proportionate to the amount of air introduced into the carbureter, thereby affording a proper mixture at all times and without regard to the speed of the engine.

Still another object is to provide a vaporizing-post of novel construction which will present a comparatively great surface of oil to the action of the passing air, thereby effecting the maximum amount of vaporization.

In the drawings forming a part of this application, Figure 1 is a side elevation of a preferred form of vaporizer constructed in accordance with the present invention. Fig. 2 is a longitudinal sectional view through the same. Fig. 3 is a vertical sectional view through the vaporizing-post preferably employed. Fig. 4 is a horizontal sectional view taken on the line 4-4 of Fig. 2. Fig. 5 is a view, partly in elevation and partly in section, of a slightly-modified form of construction.

Similar reference-numerals indicate corresponding parts in all the figures of the drawings.

In the embodiment illustrated in the first four figures a cylindrical casing 6 is employed, to the ends of which are detachably fitted heads 7 and 8, said heads being preferably screwed upon the ends of the casing. The annular wall of the casing 6 is provided contiguous to one end with an annular series of air-inlet openings 9, which are controlled

by inwardly-opening check-valves 10, covering the inner sides of the same, each of said valves being supported upon an independent spring 11, arranged longitudinally within the casing and secured at its opposite end by any suitable means—as, for instance, a screw 12. In order that the tension of the springs 11 may be varied, a ring 13 is employed, which is located within the casing and bears against the inner sides of the springs. This ring is slidably toward the heads of the casing, and actuating means in the form of threaded shanks 14 journaled in the head 7, have adjustably-threaded engagements with ears 15, formed upon the inner side of the ring. The shanks 14 have exteriorly-arranged operating-heads 16 and collars 17, arranged against the inner face of the casing-head 7 and constituting means for preventing the displacement of the shanks.

The head 7 is provided with a central opening surrounded by an integral collar 18, through which is passed the inner end of an outlet-sleeve 19, said sleeve terminating short of the head 8 and being spaced from the wall of the casing 6. The sleeve is secured in place by any suitable means—as, for instance, screws 20, threaded through the collar 18 and engaging its outer end. Said sleeve practically constitutes a part of the outlet-conduit for the vapor, which conduit also includes a T-coupling 21, secured to the outer end of the sleeve 19 by an interior collar 22. To one end of this T-coupling is attached a pipe 23, leading to the engine. The wall of the said T-coupling directly in line with the bore of the sleeve 19 is provided with an opening, through which is passed a fuel-conductor tube 24, that extends centrally into the sleeve 19, but terminates short of its inner end. The outer end of this fuel-conducting tube communicates with a primary mixing-chamber 25, formed within a coupling 26. The coupling has an air-inlet nipple 27, directly opposite the conducting-tube 24 and communicating with the chamber 25. A fuel-supply pipe 28 communicates through a needle-opening 29 with the chamber 25, between the air-inlet and the conducting-tube, said needle-opening being controlled by a needle-valve 30, formed upon the end of a stem 31, that is slidably passed through the opposite wall of the chamber. The opening through which said stem passes

is of sufficient size to receive a stop-plug 32, mounted on the stem and threaded into the walls of the opening, a lock-nut 33 being screwed upon said plug. A stop-collar 34, 15 secured to the stem 31 within the chamber 25, is arranged to abut against the inner end of the stop-plug, and thus limit the movement of the needle-valve. This entire structure is practically supported by the conducting-tube 24, which is secured to the wall of 20 the coupling 21 by means of a conical clamp-nut 35, threaded into a plug 36, that is secured to said coupling.

Arranged in line with the stem 31 of the 15 needle-valve is a hollow drum 37, the interior of which communicates with the coupling through a conduit 38, threaded into a cap 39, that closes the end of the coupling 21, opposite the engine-pipe 23. The wall of 20 this drum, which is adjacent to the preliminary mixing-chamber, is in the form of a diaphragm 40, secured in place by a suitable ring 41 and having the valve-stem attached to the central portion thereof.

25 In this structure there is preferably employed a vaporizing-post, which while it may be of any desired form is preferably constructed and arranged as follows: The lower head 8 of the casing has an outstanding boss 30 42 and a central opening 43 arranged within the boss. A supporting-nut 44 is threaded into the boss and has secured to its central portion a stem 45, that projects into the sleeve 19 in line with or spaced from the conducting-tube 24. This stem constitutes a 35 holder for a series of cup-shaped wings 46, preferably formed of wire fabric and held in spaced relation by interposed sleeves 47. These wings are preferably arranged entirely 40 within the sleeve 19 and are held in spaced relation from the lower head and the supporting-nut 44 by a longer washer 48.

The operation of the carbureter may be 45 briefly described as follows: Assuming that the engine is connected with the pipe 23, it will be evident that upon certain strokes of said engine air will be withdrawn from the interior of the carbureter. If this air is charged with vapor, said vapor will therefore be delivered to the engine. In starting the same with heavy oil it is preferable to heat said oil until the first charge of explosive mixture has been delivered and used, after which the action is automatic. When the suction 55 through the pipe 23 takes place, a partial vacuum will be formed within the entire carbureter, so that the same may be truly termed a "vacuum-chamber." The amount of this vacuum can be varied as desired by 60 adjusting the ring 13 toward or from the check-valves 10, requiring greater pressure of the outside air to open said valves. The same unbalanced air-pressure serves to move the diaphragm 40 of the drum 37 inwardly, consequently opening the needle-

valve and permitting an inflow of hydro-carbon fuel. At the same time it will be apparent that a current of air will pass through the nipple 27 into the conducting-tube 24 at right angles to the jet of oil from the orifice 29, and consequently a preliminary mixing of air and oil will take place in the chamber 25 and this rich-mixture will pass through the tube 24 into the sleeve 19. The sleeve constitutes the main mixing-chamber of the carbureter, for the current of air passing through the air-inlets 9 will enter the lower end of the sleeve and find its way through the coupling 21 to the pipe 23. At the same time the above-mentioned enriched mixture will be 80 drawn in an opposite direction from the discharge-nozzle of the tube 24. Here the oppositely-moving currents will strike, causing a thorough commingling and vaporizing of the oil before it passes to the engine. As 85 soon as the suction ceases the air-pressure within the carbureter will equalize that without and the diaphragm of the drum will return to its normal position, consequently closing the valve and cutting off the supply 90 of oil. Any oil, however, that may drip from the end of the conducting-tube 24 or not be vaporized will be caught upon the wings 46 and will spread in thin films over the spaces formed by the meshes of the wire. 95 Thus comparatively great surfaces of oil will be afforded to the free action of the air when the next inrush takes place and a vaporization of the surplus oil is obtained. The operation of the device is therefore economical, 100 as the oil is only fed as rapidly as used, so that whether the engine is running rapidly or slowly the feed will automatically accommodate itself to the same. Moreover, the amount of vacuum determines not only the 105 supply of air past the check-valves, but also the distance to which the needle-valve controlling the oil-supply is opened, and an abnormal movement of the latter is prevented 110 by the stop-nut 32, which can be threaded into or out of the chamber, so as to vary the distance of movement of the needle-valve. The manner in which the oil is vaporized is one of the important features of the invention—the preliminary mixing, and finally the 115 complete vaporization by the impinging oppositely-moving currents of air. The construction of the vaporizing-post is also worthy of note, not only on account of the advantageous way in which it presents the oil to the 120 action of the air, but also because of its simplicity of construction. By unscrewing the supporting-nut 22 the entire post may be removed and the parts thereof disassociated and reassembled with ease.

In Fig. 5 a slightly-modified form of the mechanism for operating the oil-supply valve is illustrated. The other parts of the carbureter are the same as those already described, and therefore need not again be set 125

forth in detail. In this instance the oil-supply-valve-stem is designated 29^a, and the end of the coupling opposite the supply-pipe 23 has threaded therein a drum 35^a. The inner 5 wall of this drum is in the form of a sliding plunger 38^a, having a rod 39^a, that projects through the rear wall of said drum. A supporting-ring 40 is secured to the exterior of the drum by means of a nut 41^a and carries 10 a post 42^a, which constitutes the fulcrum of a small lever or walking-beam 43^a. The valve-stem 29^a is pivoted to one end of this lever, while the plunger-rod is in like manner pivoted to the opposite end. It will be apparent 15 that the action of the device is exactly the same as that already described. When the suction takes place, the partial vacuum formed will cause the plunger 38^a to move inwardly, and through the medium of the lever 43^a the 20 valve-stem 29^a will be moved outwardly to open the oil-supply. As already stated, the other features are the same, and therefore the same reference-numerals have been employed in designating those that are shown. 25 From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages of the invention.

35 Having thus described my invention, what I claim as new, and desire to secure by Letters Patent, is—

1. In a carbureter, the combination with a preliminary mixing-chamber having fuel and 40 air inlets that introduce their respective charges into the mixing-chamber in different intersecting directions, of a secondary mixing-chamber having a freely-open communication with the preliminary mixing-chamber and also having an air-inlet, a valve controlling the fuel-inlet to the preliminary mixing-chamber, and a vacuum-compartment having communication with the secondary mixing-chamber, said compartment also having 45 a movable wall connected to the fuel-controlling valve.

2. In a carbureter, the combination with a secondary mixing-chamber comprising a depending sleeve having an inlet in its lower 55 end and an outlet at its upper end, of a preliminary mixing-chamber having air and fuel inlets and an outlet conducting-tube that depends within the sleeve, a valve for controlling the fuel-inlet, a vacuum-compartment 60 communicating with the outlet from the secondary chamber and having a movable wall, and a connection between the movable wall and the valve.

3. In a carbureter, the combination with a 65 casing having an air-inlet, of a secondary

mixing-chamber comprising a sleeve depending within the casing and having its lower end open, an offset outlet-pipe connected to the upper end of the sleeve, a preliminary mixing-chamber located above the sleeve 7^c and having air and fuel inlets, a depending fuel-conducting tube leading from the preliminary mixing-chamber downwardly into the sleeve and terminating short of the lower end thereof, a valve controlling the fuel-inlet, and a vacuum-compartment having communication with the outlet from the secondary mixing-chamber, said compartment having a movable wall connected with the valve.

4. In a carbureter, the combination with a casing, of a secondary mixing-chamber comprising a sleeve depending within the casing and terminating short of the lower portion thereof, said casing having air-inlets, an offset outlet-pipe leading from the upper end of the sleeve, a preliminary mixing-chamber mounted upon the pipe and located above the secondary chamber, said preliminary mixing-chamber having an upper air-inlet 85 and a lower outlet, a conducting-tube leading from said outlet and depending within the sleeve, a fuel-inlet pipe leading to the preliminary mixing-chamber between the air-inlet and the outlet, a needle-valve controlling the fuel-inlet and extending across the preliminary mixing-chamber, a drum having communication with the outlet from the secondary mixing-chamber and also having a diaphragm-wall, and a connection between said wall and the fuel-controlling valve.

5. In a carbureter, the combination with a casing having air-inlet openings therethrough, of fuel-mixing means including a 105 tubular wall located longitudinally within and in spaced relation to the walls of the casing, said tubular wall defining a mixing-chamber that has open communication with the interior of the casing, a plurality of leaf-springs arranged longitudinally between said tubular wall and the walls of the casing, means for securing each spring at one end, and a valve carried by the other end and covering one of the openings.

6. In a carbureter, the combination with a casing having an annular series of air-inlet openings contiguous to one end, of a vapor-outlet pipe extending through said end of the casing and terminating short of the opposite 110 end, means for introducing fuel into the vapor-outlet pipe, a plurality of springs secured longitudinally within the casing, and valves carried by the free ends of the springs and located over the inlet-openings of the 115 casing.

7. In a carbureter, the combination with a secondary mixing-chamber comprising a depending sleeve having a lower air-inlet and an upper outlet, of a preliminary mixing- 130

chamber located above the secondary mixing-chamber and having fuel and air inlets, and a conductor-tube leading from the lower portion of the preliminary mixing-chamber 5 downwardly into and depending within the secondary chamber.

8. In a carbureter, the combination with a preliminary mixing-chamber, of air and fuel inlets thereto, a main mixing-chamber having an air-inlet and a vapor-outlet, and means for directing the mixed air and fuel from the preliminary mixing-chamber to the main mixing-chamber and in a direction opposite to the direction of flow of the air 15 passing through the inlet to the outlet of said main chamber.

9. In a carbureter, the combination with a secondary mixing-chamber, comprising a depending sleeve having a lower air-inlet and 20 an upper outlet, of a preliminary mixing-chamber located above the secondary chamber and having an upper air-inlet and a lower outlet, a conductor-tube leading from the outlet downwardly into the secondary 25 chamber in opposition to the flow of air therethrough, a lateral fuel-inlet in the preliminary mixing-chamber, and means for controlling the passage of fuel therethrough.

10. In a carbureter, the combination with 30 a secondary mixing-chamber comprising an upright sleeve having an air-inlet at its lower end, of an offset outlet-pipe communicating with the upper end of the sleeve, a preliminary mixing-chamber supported above the 35 upper end of the sleeve and the pipe and having an air-inlet in its upper end, and an outlet in its lower end alined with said inlet, a conductor-tube leading from the outlet of the preliminary chamber downwardly into 40 the secondary chamber in spaced relation to the sleeve, a lateral fuel-inlet leading to the preliminary chamber between the air-inlet and the outlet thereof, and a valve for controlling the supply of fuel through said inlet.

11. In a carbureter, the combination with a 45 casing having air-inlets, of a vapor-outlet pipe extending into the casing from one end and terminating short of the other end, the inner end of said vapor-outlet pipe constituting a 50 mixing-chamber, a preliminary mixing-chamber having fuel and air inlets, and a conductor-tube leading from the preliminary mixing-chamber into the outlet-pipe and longitudinally of the portion thereof that is 55 located within the casing, said conductor-tube terminating short of the inner end of said outlet-pipe.

12. In a carbureter, the combination with a 60 casing having air-inlets, of a vapor-outlet pipe extending into the casing from one end and terminating short of the other end, the inner end of said vapor-outlet pipe constituting a mixing-chamber, a preliminary mixing-chamber having fuel and air inlets, a 65 conductor-tube leading from the preliminary

chamber into the outlet-pipe and longitudinally of the portion thereof that is located within the casing, said conductor-tube terminating short of the inner end of said outlet-pipe, and a vaporizing-post secured to the casing and extending longitudinally within the inner end of the outlet-pipe in opposition to the conductor-tube. 70

13. In a carbureter, the combination with a cylindrical casing having an annular series 75 of air-inlets contiguous to one end, a plurality of check-valves controlling said inlets, a vapor-outlet pipe extending longitudinally into the casing from the end having the inlet-openings and terminating short of the opposite end, a vaporizing-post secured to said opposite end and projecting into the vapor-outlet pipe, a preliminary mixing-chamber having air and fuel inlets, a valve for controlling the fuel-inlet, and a conductor-tube 80 leading from the preliminary mixing-chamber into the vapor-outlet pipe and in opposition to the vaporizing-post.

14. In a carbureter, the combination with a mixing-chamber having an inlet and an 90 outlet, of a fuel-conducting tube extending longitudinally thereto and terminating short of one end thereof, and a post projecting into said mixing-chamber from said end and in opposition to the tube, said post having a 95 perforate portion arranged to receive the fuel and permit the passage of air therethrough.

15. In a carbureter, the combination with a mixing-chamber having a lower air-inlet and 100 an upper outlet, of a fuel-conducting tube extending through the upper end of the chamber and depending within the same, said tube terminating short of the lower end of the chamber and being spaced from the side 105 walls thereof, and a post projecting into the lower end of said chamber in spaced relation to the side walls thereof, said post having perforate portions located in line with the conducting-tube and in spaced relation thereto, said perforate portions receiving the fuel and permitting the passage of air. 110

16. In a carbureter, the combination with a 115 casing, of a mixing-chamber located therein and comprising a depending sleeve terminating short of the lower end of said casing, a head closing the lower end of the casing, a non-heated vaporizing-post detachably secured to the lower end of the head and projecting within the sleeve in spaced relation to the side wall thereof, and a depending fuel-conducting tube extending through the top of the sleeve in spaced relation to the side walls thereof and terminating short of the upper end of the post. 120

17. In a carbureter, the combination with a mixing-chamber, of a fuel-conducting tube extending into the same, and a vaporizer-post also extending into the chamber in opposition to the tube, said post comprising a 130

stem, and a plurality of perforate wings mounted thereon.

18. In a carbureter, the combination with a mixing-chamber, of a fuel-conducting tube leading thereto, and a vaporizing-post supported within the chamber and adapted to receive the fuel from the tube, said post comprising a stem and a series of spaced cup-shaped perforate wings mounted on the stem in line with the tube.

19. In a carbureter, the combination with a vacuum-chamber, of a mixing-chamber communicating therewith and having an air-inlet in line with such communication, a fuel-supply pipe having a discharge-orifice communicating with the mixing-chamber and directing a jet transversely of the inlet, a needle-valve controlling the orifice of the fuel-supply pipe and having a stem extending across the mixing-chamber, a drum arranged in line with the stem exteriorly of the mixing-chamber and having a diaphragm-wall connected thereto, and a conduit connecting the interior of the drum and the vacuum-chamber.

20. In a carbureter, the combination with a casing having a plurality of air-inlets, of a plurality of separately-movable springs, check-valves carried by the springs and controlling the air-inlets, and common means movable along the springs for varying the resistance thereof to the opening movements of the valves.

21. In a carbureter, the combination with a casing having an air-inlet, of a spring supported at one end and carrying a valve at the other end that controls the inlet, and a device movable longitudinally of and coacting with the spring to vary the amount of resistance to the opening of the valve.

22. In a carbureter, the combination with a casing having a plurality of air-inlets, of a plurality of springs secured to the casing and having valves controlling the air-inlets, and a ring movable with respect to and coacting with the various springs to vary the amount of resistance to the opening of the valves.

23. In a carbureter, the combination with a casing having an annular series of air-inlet openings, of a plurality of springs each secured at one end within the casing and disposed longitudinally thereof, valves carried by the free ends of the springs and closing

the air-inlet openings, a ring arranged within the casing and slideable longitudinally with respect to the valves, and actuating means for adjusting the ring.

24. In a vaporizer, an air-supply passage, an air-throttle valve therein, with spring to control the opening of said valve and means for adjusting the active length of the spring.

25. Means for governing the introduction of air into a carbureter, comprising a ported part coöperating with the carbureter and provided with a valve having an inherent spring tendency, said valve being fixed at one end and free at the other end for normally closing said ported part, and a longitudinal sliding means within the ported part and coöperating with said valve to vary the movement of the free end thereof, substantially as described.

26. Means for governing the introduction of air into a carbureter, comprising a ported part coöperating with the carbureter, a vibratory valve having an inherent yielding tendency, said valve being fixed at one end and free at the other for normally closing said ported part, and means within the ported part and longitudinally movable between the free and fixed ends of the valve for varying the movement of said valve, substantially as described.

27. In a device of the class described, the combination with a tube having longitudinal slots therein, yielding means for valving the said slotted tube, and a sliding device within the tube and coöperating with the yielding means to vary the yieldability thereof so as to govern the admission of air into the tube, substantially as described.

28. In a device of the class described, a ported tube closed at one end, yielding valve-plates for closing the ports of the tube, and a threaded stem passing through the closed end of the tube and having means for governing the yieldability of the valves, substantially as described.

In testimony that I claim the foregoing as my own I have hereto affixed my signature in the presence of two witnesses.

JAMES J. COOK.
